UNITED STATES PATENT OFFICE.

GUSTAVE SCHWAB, OF NEW YORK, N. Y., ASSIGNOR TO THE SCHWAB MANUFACTURING COMPANY, OF SAME PLACE.

SUPPORT FOR ALBUMS OR OTHER OBJECTS.

SPECIFICATION forming part of Letters Patent No. 669,903, dated March 12, 1901.

Application filed October 20, 1900. Serial No. 33,775. (No model.)

To all whom it may concern:

Be it known that I, GUSTAVE SCHWAB, a citizen of the United States, residing at Manhattan borough, New York city, in the county 5 and State of New York, have invented new and useful Improvements in Supports for Albums or other Objects, of which the following is a specification.

This invention relates to a support which, 10 while it can be readily set up in the form of an easel, can also be readily dismounted or packed in flat or compact shape for shipping or storing; and the invention resides in the 15 novel features of construction set forth in the following specification and claim and illustrated in the annexed drawings, in which—

Figure 1 is a sectional side elevation of a support embodying this invention. Fig. 2 is a face view of Fig. 1. Fig. 3 is a perspective 20 view of the support dismounted.

In the drawings is shown an easel or easel-support composed of a back *a* and a drawer or box removable from the back—that is to say, the shell *b* of the drawer is removable, 25 the drawer proper or sliding part *c* being in said shell. The back *a* is of suitable form, closed work or skeleton, and the entire device of desired shape and material and plain or ornamented, as may be called for. The 30 back *a* is shown with an opening or seat *d*, and when the box or receptacle *b* is slipped or seated in this opening, the back resting on its lower edge and the box resting on its rear lower edge, the back is held at a tilt or at what 35 might be called "easel" position or inclination. This detachable drawer thus performs a dual function as a box or receptacle and also as a support for the back. When the drawer is detached from the back or drawn 40 out of its seat *d*, the back and drawer can be laid or packed flat or in compact manner, Fig. 3. The cut *d* is shown in Fig. 2 with its upper edge or part thereof arched or cutaway, which cut can form a passage, for example, to 45 allow a projection or key *e* to pass, as in case a music-box or the like is contained in the drawer *b*; but of course these details do not affect the invention, and the shape or ornamentation of passage *d* can be varied as 50 called for.

In an example made the rearwardly-ex-

tended drawer *b* was provided with a ledge *f*, and the ledge being ornamented or covered in conformity with the back *a* or its face and the front wall of the drawer part or slide *c* 55 gave the whole a neat and salable appearance. This ledge *f* is of practical use, as it can form a shoulder or stop, which, striking an edge part of or being arrested at opening *d*, will enable the drawer to be readily inserted into the back to the proper extent.

The easel or back *a* can serve as a support for an object—as, for example, a mirror, picture, or other article. In practice this easel has been applied to swingingly support an album *g*, which, resting its back on the ledge *f*, can be opened and closed in the manner known in the so-called "easel-albums." These albums are suitably suspended or hinged to the easel, as by hooks and eyes *h* and *i* or by 65 other connecting means, as bails, yokes, and the like known in the art. When closed, the album hangs with its back resting on or near to the ledge *f*, so that when the front cover of the album opens and swings down, followed successively by the album-leaves, the 70 album-back rests or is supported on this ledge or shelf *f* or on the drawer *b*.

The drawer can serve as a receptacle for various objects—as, for example, pictures, 80 brushes, and other articles.

The album can of course be ornamented or given an appearance as called for by the easel, and the detachable or separable fastenings or hinges *h* *i* enable the album to be taken from 85 the easel to be laid flat, as for inspection or when to be packed, shipped, or stored. The example shown in the drawings was one having the face of back *a* and the face of the front of drawer *c*, as also the ledge *f* and album *g*, covered or ornamented with plush; but of course the ornamentation can be varied without departing from the invention.

In place of a ledge *f* any other suitable projection or stop can be employed for securing 95 proper position of the drawer relative to the seat *d* or back *a*.

A handle or hanger *k* can be secured or hinged to back *a* if thought desirable.

What I claim as new, and desire to secure 100 by Letters Patent, is—

In a support for albums and the like, a back

provided with a suitable opening, a receptacle extending through said opening for supporting the back at an inclination and provided with a drawer, a wedge-shaped ledge 5 mounted upon said receptacle, forming a stop therefor, and a support for the album or the like, and a hook carried by said back for engagement with the album or the like.

In testimony whereof I have hereunto set my hand in the presence of two subscribing witnesses.

GUSTAVE SCHWAB.
